(57) **CLAIM**

The ornamental design for a tweezer, as shown and described.

DESCRIPTION

FIG. 1 is a top perspective view of a tweezer in accordance with the present design.

FIG. 2 is a left side view of a tweezer. The right side view of a tweezer is a mirror image of the left side view of the tweezer shown in FIG. 2.

FIG. 3 is a top view of a tweezer.

FIG. 4 is a back view of a tweezer; and,

FIG. 5 is a front view of a tweezer.

The broken lines shown in the drawings illustrate portions of the article and form no part of the claimed design.
